DISPENSER FOR PHOTOGRAPHIC PAPER

Sidney Barzman, Brooklyn, and Saul S. Weitzman, Bethpage, N.Y., assignors to B.B.M. Manufacturing Corporation, New York, N.Y., a corporation of New York

Application February 24, 1959, Serial No. 54,710

Term of patent 14 years

(Cl. D52—2)

Fig. 1 is a perspective view of the dispenser for photographic paper with the cover in normal position, embodying our design.

Fig. 2 is a perspective view thereof with the cover slidably moved rearwardly to dispensing position.

Fig. 3 is an end view thereof as viewed from the right hand end of Fig. 1.

Figs. 1 and 2 of the drawing are lined to represent the cover as being of contrasting color to the body of the dispenser.

We claim:

The ornamental design for a dispenser for photographic paper, as shown and described.
